Attorney

UNITED STATES PATENT OFFICE

EUGENE A. HOLMGREEN, OF SAN ANTONIO, TEXAS

COTTON TRAMPER AND THE LIKE MACHINE

Application filed November 29, 1930. Serial No. 499,094.

This invention relates to reciprocating machines and particularly to machines adapted for use as cotton trampers, pump jacks and the like and the object of the invention is to provide a new and improved machine of this kind in which the strains and stresses will be better equalized throughout the frame work of the device and in which the reciprocated element will be caused to travel a greater distance than its operating mechanism.

Further objects and advantages will become apparent as the description proceeds.

Referring to the accompanying drawings, which are made a part hereof and on which similar reference characters indicate similar parts,

Figure 1 is a view in elevation of the device,

Figure 2, a portion of a vertical section,

Figure 3, a section on line 3-3 of Figure 2, and

Figure 4, a modified form of the device showing it acting as a pump instead of a cotton trumper.

In the drawings numerals 10 and 11 indicate the frame work and supporting table respectively of a cotton trumper and 12 and 13 indicate vertical plungers having trumper shoes 14 on their lower ends. The plungers 12 and 13 preferably are secured together at their upper ends by a beam or bar 15. Operating mechanism for vertically reciprocating the plungers is housed in a casing 16 and 30 consists of a shaft 17 driven by a pulley 18 from any suitable source of power. On the inner end of the shaft 17 is provided a worm 19 meshing with a worm wheel 20 on a shaft 21. The outer ends of the shaft 21 are provided with crank arms 22 which are connected by links 23 with a cross head 24.

The cross-head is provided with rollers or other guiding means 25 held between guide posts 26. The outer arms of the cross head 45 are provided also with rollers 27 for retaining and guiding the vertical plungers 12 and 13. A pair of sprocket wheels 28 and 29 is rotatably mounted at one side and a similar pair 34 and 35 at the opposite side of the cross head. A sprocket chain 30 is secured

at one end near the upper end of a guide beam 26 and secured at its other end near the top of one of the plungers 12. Another sprocket chain 31 is secured at its lower end to the guide post 26 and at its other end to the plunger 12. Similar sprocket chains 32 and 33 are secured in alternate relation to sprocket wheels 34 and 35. From the description so far given it should be apparent that vertical movement of the cross-head will rotate the sprocket wheels and that this rotation will transfer movement to the plungers 12 and 13. It should be apparent moreover that as the cross head moves upward, for example, sprocket wheels 28 and 35 will rotate 65 in a clockwise direction and that this rotation will wind sprocket chains 31, 30, 32 and 33 in a direction to move the plungers 12 and 13 upwardly and that these plungers will travel vertically twice the distance through 70 which the cross-head itself moves. By the use of sprocket chains as shown the strains incident to reciprocating the heavy trampers are transferred throughout half the circumference of the sprocket wheels. In 75 my prior Patent 1,751,332 trumper beams are reciprocated vertically by having sprocket wheels engage directly with sprockets on the trumper beams. In this patent the entire strain and stress is carried by a few 80 sprocket teeth on the sprocket wheels. With the present device trumper beams of equal weight or even greater weight may be operated by much smaller sprocket wheels due to the fact that the weight is carried by 85 larger areas on the wheels. This enables me to get a machine which will do the same work but which machine is much lighter in weight than with machines heretofore built. By 90 positioning the driving or lifting sprocket chains and wheels in an alternate relation the stresses are more evenly distributed through the whole machine. This enables me to secure the same results with a small machine 95 that were secured heretofore with machines having heavy frame structures.

In Figure 4 my device is shown adapted for use as a pump jack in which the trumper shoes are replaced by a cross beam or bar 100

36 to which the sucker rod 37 of a pump is attached. The well is indicated by 38.

While one embodiment of the invention has been specifically described and illustrated in which the operated plunger moves a distance double that of the operating cross head, the invention is not limited to such construction.

Various modifications of the invention may be made in which the operated plunger may move a distance greater than or less than double that through which the operating cross head moves. All of these modifications are held to be within the purview of the invention.

It will also be obvious to those skilled in the art that further various changes may be made in my device without departing from the spirit of the invention and therefore I do not limit myself to what is shown in the drawings and described in the specification, but only as indicated by the appended claim.

Having thus fully described my said invention, what I claim as new and desire to secure by Letters Patent, is:—

An apparatus of the class described comprising a base, a pair of vertical stationary I beams slidably mounted in said base, a cross-head slidably mounted on said I-beams and composed of a pair of diamond-shaped plates mounted one on each side of said I-beams, guide rollers mounted between each point of said plates and riding in said I-beams, twin sprockets carried by said cross-head between said stationary I-beams and said slidable I-beams, chains secured to the top and bottom of said stationary I-beams and passing beneath and above said sprockets respectively and secured adjacent the top and bottom of said slidable I-beams, a pair of connecting rods secured to said triangular plates, and a crank for operating the same to cause a reciprocating motion to said slidable I-beams, substantially as set forth.

In witness whereof, I have hereunto set my hand and seal at San Antonio, Texas, this twenty-fourth day of November, A. D. nineteen hundred and thirty.

EUGENE A. HOLMGREEN.
